COMBINED GAME APPARATUS AND ASH TRAY OR SIMILAR ARTICLE

Paul Rossi, Warren, Ohio

Application April 23, 1954, Serial No. 30,154

Term of patent 14 years

(Cl. D34—5)

To all whom it may concern:

Be it known that I, Paul Rossi, a citizen of the United States of America, residing at Warren, in the county of Trumbull and State of Ohio, have invented a new, original, and ornamental Design for a Combined Game Apparatus and Ash Tray or similar article, of which the following is a specification, reference being had to the accompanying drawing, forming a part thereof.

Fig. 2 is a side elevational view thereof, partly in cross section.

Fig. 3 is a top plan view thereof.

The back of the article, not shown, is substantially plain or conventional. The dominant features of my new design are shown in solid lines in the drawing.

I claim:

The ornamental design for a combined game apparatus and ash tray or similar article, as shown and described.
